STAMP MOUNT

Harry Brodsky, Philadelphia, Pa.

Application September 4, 1947, Serial No. 772,100

3 Claims. (Cl. 40—159)

1

This invention relates to stamp display mounts wherein the entire face of the stamp is visible and wherein the stamp will be protected in an album.

Heretofore, in mounting stamps for display in album it has been the practice to do so by means of gummed paper hinges or by means of transparent envelopes. When the hinge is used, one half of it is attached to the album page and the other half to an edge portion of the stamp. With this arrangement the stamp is secured only along an edge thereof by a small piece of paper and is difficult to keep in alignment to present a neat appearance. Furthermore, since the stamps may extend upwardly about their hinged edges they are often unintentionally folded over upon themselves and creased between the closing pages of an album. Also, when these stamps are removed from the album there is the objection that a portion of the hinge is permanently attached thereto, the removal of which often results in damage to the stamp.

When a transparent envelope is used to mount a stamp, it is customarily attached along the rear face thereof to the album page in such manner as to normally require the use of tweezers on the stamp to insert or to remove the same therefrom. This method of mounting the stamps often results in injury thereto when the serrated stamp edges catch upon the open edges or the flap of the envelope. Furthermore, the envelopes so mounted often obscure the printed matter usually provided in the albums within the space set aside for the mounting. In addition, the stamp being loose within the envelope is free to shift relatively thereto and consequently it is difficult to maintain the stamps so mounted in alignment to present a neat appearing album.

Accordingly, it is an object of this invention to provide a quadrangular shaped stamp mount comprising a transparent renitent face member and a suitably colored non-transparent backing member secured together in flat superimposed relation only along edge portions of the opposed inner faces thereof, such stamp mount being of such character, design and function as to permit the entire face of the stamp to be visible within a framing border and maintain the stamp in the position in which it is originally placed therein.

It is a further object of the present invention to provide a stamp mount as described with means to attach the same to an album along the rear face of the backing member at an edge portion which is opposite to the edge portion thereof secured to the face member, whereby when the mount is raised about the attached edge portion of its backing member to view the

2

printed matter beneath the same, the stamp, together with the protective transparent face member of the mount, shifts substantially in its own plane and so remains disposed in relatively flat condition.

Other objects and advantages of this invention will appear more fully hereinafter, it being understood that the present invention consists substantially in the construction, combination, location and relative arrangement of parts, all as will be more fully hereinafter set forth, as shown in the accompanying drawings, and as finally pointed out in the appended claims.

In the drawings—

15 Figure 1 is a front view showing several stamp mounts on a portion of an album page, one of the mounts being in raised position and another having a portion of the face member thereof broken away;

20 Figure 2 is a sectional view taken on line 2—2 of Figure 1;

Figure 3 is a view similar to that shown in Figure 2 but with the mount raised about its fixed edge;

25 Figure 4 is an enlarged sectional view of a detail taken on line 4—4 of Figure 1;

Figure 5 is an enlarged sectional view of a detail taken on line 5—5 of Figure 1;

30 Figure 6 is a perspective view showing the mount in strip form; and

Figure 7 is a sectional view taken on line 7—7 of Figure 6.

The stamp mount of the present invention comprises two similarly shaped quadrangular pieces of sheet material, of which one is a transparent renitent face member and the other a dark colored non-transparent backing member, secured together in flat superimposed relation only along corresponding edge portions of the opposed inner faces thereof. It is adapted to be mounted upon an album page by being attached thereto along the rear face of the backing member at the edge portion thereof which is opposite to the edge portion secured to the face member.

45 As shown in the drawings, the stamp mount is made of a suitably colored non-transparent quadrangular shaped backing member 10 of sheet material, preferably heavy paper or light weight cardboard, and of a similarly shaped renitent transparent face member 11, also of sheet material, preferably cellophane or other transparent plastic material, having renitent characteristics, the two members being secured together in flat superimposed relation (see Figure 7) only along the bottom edge portions 12 of the opposed inner faces thereof by any suitable means, such as glue

or cement 13. The backing member 10 of the mount is preferably of a color of such contrast with that of the stamp that when a stamp, such as 14, is displayed therein that portion of the member 10 not covered by the stamp will provide a contrasting framing border 15 around the same visible through the transparent face member 11.

The stamp mount is adapted to be mounted upon an album page 16 by being attached thereto along the rear face of the backing member 10 at upper edge portion 17 thereof by any suitable means, such as glue or cement 18 applied thereto. It will be noted that the edge portion 12 of the mount is freely disposed relatively to the album page.

A stamp may be placed in the mount, preferably after the same has been attached to an album page, by first springing the face member 11 away from the backing member 10 along the secured edge portions thereof and then inserting the stamp therebetween by hand or with the aid of tweezers so that the stamp is centered within the mount with its lower edge frictionally secured between the joined lower edges of the members 10 and 11. Thus, when the face member 11 is permitted to spring back toward the backing sheet the stamp will be held securely therebetween with an edge portion thereof wedged tightly between the inner faces of the mount members adjacent the edge portions 12 thereof. In this manner the stamps will remain in the mounts in the position they are originally placed therein so that it becomes an easy matter to permanently align the stamps to present a neat appearing album. It is to be noted that the mount is open along three edges thereof so that when the face member 11 is sprung away from the backing member 10 there is free unrestricted access to the space therebetween.

If it should be desired to raise an attached mount and inserted stamp to inspect the album beneath the same, as is shown to the right of Figure 1, this can readily be done by lifting the edge 12 of the mount and raising the same about the attached edge 17 of the backing, as shown in Figure 3. In this position of the mount, while the backing member 10 is adapted to be curved or bent, the face member 11, being renitent, separates from the backing sheet and slides along the album page together with the stamp so that in the raised position of the mount, while the backing member 10 is bent, the transparent face sheet 11 and the stamp are in relatively flat disposition. This is so because the mount is open along three edges thereof permitting relative movement between the members and because the face member is of such relatively stiff material as to provide an adequate supporting surface for the stamp along which it may shift substantially in its own plane.

In the manufacture of the mount shown herein the same may be made of long continuous strips of suitable materials, as shown in Figure 6, with the transparent face and opaque back members secured together along edge portions thereof as described, such strip being adapted to be severed along dotted lines 19 to provide individual stamp mounts of any desired size. It may also be desirable to manufacture the mount in the strip form shown in Figure 6 for the purpose of having a single lengthwise extending strip mount wherein a number of stamps may be displayed alongside each other.

It will be obvious that I have provided an improved economical transparent type stamp

mount which is attachable to an album page and within which one or more stamps may readily be placed for safe and attractive display of the same.

It is to be understood that various arrangements and modifications other than that described above may be devised, and yet come within the spirit of the invention. Accordingly, it is the intention that the appended claims be construed broadly to cover such alternative arrangements and modifications.

What is claimed as new and useful is:

1. A stamp mount adapted to be secured to a supporting album page or the like comprising in unitary assembly a substantially rectangular shaped transparent renitent face member and a like shaped non-transparent backing member arranged in flat superimposed relation and secured together along single corresponding edges thereof by an intervening film of adhesive applied marginally along said secured edges, said mount being adapted to receive a stamp between said members and to wedge the same in position therebetween.

2. A stamp mount comprising a substantially rectangular shaped transparent renitent face member of relatively stiff sheet material, and a like shaped non-transparent backing member of relatively stiff sheet material, said members being arranged in flat super-imposed position one upon the other with their corresponding marginal edges in substantial registry and secured together along corresponding single edges thereof by an intervening film of adhesive applied marginally along said secured edges, said mount being adapted to receive a stamp between said members to wedge the same in position therebetween, and means for securely attaching said mount to an album page along an edge of said backing member opposite that secured to the facing member whereby the secured edges of said mount are disposed freely with respect to said album page.

3. A stamp mount comprising in unitary assembly a substantially rectangular shaped transparent renitent face member and a like shaped non-transparent backing member disposed in flat superimposed relation with their corresponding marginal edges in substantial registry, a film of adhesive material disposed between marginal portions of corresponding single edges only of said superimposed members to secure the same together along said edges and provide a stamp pocket open on three sides thereof, said pocket being adapted to receive a stamp therein with one edge thereof wedged between the marginally secured portions of the stamp pocket, the backing member of this mount being adapted to be hinged to an album page along the edge thereof which is opposite that secured to said face member so that the body of said mount may be lifted from the album page without disturbing the flat-wise disposition of the face member and of the stamp protected thereby.
